UNITED STATES PATENT OFFICE.

WILLIAM A. BLAKESLEY, OF BAKER, OREGON.

APPARATUS FOR RAISING SUBMERGED VESSELS.

1,207,481.

Specification of Letters Patent.

Patented Dec. 5, 1916.

Application filed November 12, 1915. Serial No. 61,184.

To all whom it may concern:

Be it known that I, WILLIAM A. BLAKESLEY, a citizen of the United States, residing at Baker, in the county of Baker and State of Oregon, have invented new and useful Improvements in Apparatus for Raising Submerged Vessels, of which the following is a specification.

This invention relates to improvements in apparatus for raising sunken vessels.

In carrying out the present invention, it is my purpose to provide apparatus of the class described which may be permanently secured to the vessel and which, when the vessel has sunk, will indicate the location of such vessel and form a guide for the lifting mechanism so that the latter may be carried directly to the ship when let down into the water and secured to the ship to facilitate the raising thereof.

With the above and other objects in view, the invention consists in the construction, combination and arrangement of parts hereinafter set forth and falling within the scope of the claims.

In the accompanying drawings; Figure 1 is a fragmentary longitudinal sectional view through a ship equipped with apparatus constructed in accordance with the present invention, the apparatus being shown in side elevation. Fig. 2 is a top plan view of the same. Fig. 3 is an enlarged vertical sectional view through the apparatus installed in the ship. Fig. 4 is a horizontal sectional view on the line 4—4 of Fig. 1. Fig. 5 is a similar view on the line 5—5 of Fig. 1. Fig. 6 is a perspective view of the device attached to the lifting cable. Fig. 7 is a vertical sectional view through such device. Fig. 8 is a diagrammatic view showing the apparatus in use.

Referring now to the drawings in detail, 1 designates the deck of a ship, while 2 indicates a frusto-conical casing seated upon the deck 1 and having the lower edge formed with an annular flange 3 provided with bolt holes through which and the adjacent portion of the deck are passed securing bolts 4 whereby the casting may be secured to the deck of the ship. Disposed within the casing 2 and suitably secured therein is an inverted conical shaped tube 5 having the upper relatively large end projecting outwardly through the relatively small end of the casing 2 and formed in the deck 1 in line with the center of the tube

5 is an opening 6. Fastened to the bottom of the deck 1 below the casing 2 and tube 5 and depending from the deck are hangers 7 and journaled in the lower ends of the 60 hangers 7 is a shaft 8 carrying a drum 9 and secured to and wrapped about the drum 9 is a cable 10. Seated upon the upper end of the tube 5 is a float or buoy 11 of any suitable construction. The outer end of the 65 cable 10 is carried through the opening 6 and secured to the float or buoy 11, as at 12. Suitably secured to the inner wall of the tube 5 adjacent to the upper end thereof and spaced apart around the tube equal distances are pairs of pivot ears 13 and pivoted between the pairs of ears 13 respectively are holding dogs 14 having the lower ends thereof projecting downwardly into the tube and the other extremities projecting up- 70 wardly toward the upper edge of the tube. 75

15 designates a lifting device comprising, in the present instance, an inverted frusto-conical shell 16 of such dimensions as to fit into the lower end of the tube 5. Arranged 80 centrally of the shell 16 and extending longitudinally thereof is a guide tube 17 suitably secured within the shell and fastened to the upper end of the guide tube 17 is a yoke 18.

In practice, when the vessel equipped with my apparatus sinks, the float or buoy 11 is supported on the surface of the water and as the vessel descends the cable 10 is unwound from the drum 9. The upper surface of the buoy or float 11 is preferably equipped with a strong reflecting plate 19 so that the buoy may be observed from a distance, incident to the light reflected by the plate 19 in the tossing of the buoy by 90 the waves.

The relief ship carries the lifting device 15 and the floating buoy enables the crew of the relief ship to locate a sunken vessel. After the sunken vessel has been located, the 100 buoy is lifted up on the relief ship and removed from the upper end of the cable, and the cable passed through the guide tube 17 in the shell 16 of the lifting device 15. The lifting cable is then secured to the yoke 18 105 and the lifting device permitted to slide down the cable 10 and is guided by the cable 10 into the tube 5 on the sunken vessel and as the lifting device drops into the tube 5, such device passes the dogs 14 and is engaged by the lower ends thereof and held in the tube 5 so that when a pull is exerted 110

upon the lifting cable, the vessel may be raised.

It will, of course, be understood that each vessel may be equipped with any number 5 of casings 2 and tubes 5 and their associated parts so that the corresponding number of lifting devices 15 may be guided into and secured within the respective tubes 5 to facilitate the lifting of the vessel.

10 The lower ends of the tube 5 and casing 2 are preferably formed with alining openings 20 through which sediment and the like may be discharged when the lifting device 15 is guided into the lower end of the 15 tube 5. This lifting device is composed of metal so that the same may readily submerge and may be weighted, if necessary.

While I have herein shown and described one preferred form of my invention by way 20 of illustration, I wish it to be understood that I do not limit or confine myself to the precise details of construction herein described and delineated, as modification and variation may be made within the scope of 25 the claims and without departing from the spirit of the invention.

I claim:

1. In apparatus for raising sunken vessels, a tube secured to the deck of the vessel, 30 dogs pivoted to the inner surface of said tube adjacent to the upper end thereof

and spaced apart, a lifting device adapted to enter said tube and pass the dogs therein whereby the dogs will hold the device within the tube, a lifting cable connected to said 35 device, a frusto-conical casing surrounding said tube and secured thereto, and connections between the lower end of said casing and the deck of the vessel, said tube and casing being formed with alining openings 40 through which sediment may be expelled under the action of said lifting device when the latter enters the tube.

2. In apparatus for raising sunken vessels, a tube secured to the deck of the vessel, 45 holding means in said tube, a lifting device adapted to enter said tube and engage said holding means, a lifting cable connected to said device, a casing surrounding said tube and secured thereto, and connections between the lower end of said casing and the deck of the vessel, said tube and casing being formed with alining openings through 50 which sediment, etc., may be expelled under the action of said lifting device when the 55 latter enters the tube.

In testimony whereof I affix my signature in presence of two witnesses.

WILLIAM A. BLAKESLEY.
